US00D954600S

(12) **United States Design Patent** (10) Patent No.: **US D954,600 S**
(45) Date of Patent: ** Jun. 14, 2022

(54) **VEHICLE FRONT GLASS**

(71) Applicant: **Canoo Technologies Inc.**, Torrance, CA (US)

(72) Inventors: **Richard Kim**, Los Angeles, CA (US); **Brian Oh**, Rancho Palos Verdes, CA (US); **Jackson E. Luttig**, Rancho Palos Verdes, CA (US); **Brian Spencer**, Lakewood, CA (US); **Noah Hammersten**, Studio City, CA (US)

(73) Assignee: **Canoo Technologies Inc.**, Torrance, CA (US)

(**) Term: **15 Years**

(21) Appl. No.: **29/804,297**

(22) Filed: **Aug. 19, 2021**

Related U.S. Application Data

(60) Division of application No. 29/746,628, filed on Aug. 14, 2020, which is a continuation of application No. 29/742,026, filed on Sep. 24, 2019.

(57) **CLAIM**

The ornamental design for vehicle front glass, as shown and described.

DESCRIPTION

FIG. 1 is a front view of vehicle front glass according to an embodiment of the invention;

FIG. 2 is a rear view thereof;

FIG. 3 is a left side view thereof;

FIG. 4 is right side view thereof;

FIG. 5 is a top view thereof; and,

FIG. 6 is a perspective view thereof.

Features shown in broken lines do not form part of the claimed design.

1 Claim, 6 Drawing Sheets
